UNITED STATES PATENT OFFICE.

FRANCIS O. WILLIAMSON, OF CHICAGO, ILLINOIS.

CRUSHING MILL.

1,413,644.

Specification of Letters Patent. Patented Apr. 25, 1922.

Application filed June 10, 1918. Serial No. 239,123.

To all whom it may concern:

Be it known that I, FRANCIS O. WILLIAMSON, a citizen of the United States, residing at Chicago, in the county of Cook and State 5 of Illinois, have invented certain new and useful Improvements in Crushing Mills, of which the following is a specification, reference being had to the accompanying drawing, forming a part thereof.

10 This invention relates more particularly to crushing or grinding mills having substantially cylindrical rotating drums, barrels or shells, with or without loose, non-friable balls, pebbles or crushing bodies, for 15 crushing, grinding or pulverizing ore, rock or other material either wet or dry, by the tumbling action and consequent impact and attrition of such bodies, or of the lumps or pieces of material to be treated, or of both 20 upon one another.

The main objects of the invention are to increase the effective crushing action both by impact and attrition of the crushing bodies or lumps of material upon one another; to facilitate the discharge of the material as soon as it is reduced to the desired size, whereby the production of slimes and their detrimental cushioning effect on the action of the crushing bodies and larger 30 pieces of material is reduced; and generally to increase the efficiency and improve the construction and operation of grinding mills of the above mentioned type.

The invention consists in the construction, arrangement and combination of parts as hereinafter particularly described and pointed out in the claims, and comprises generally a rotary drum, barrel or shell, and one or more internal displacement members 40 located at or adjacent to either or both ends of the drum, or at one or more intermediate points in its length and of varying extent lengthwise of the drum, so as to impart movement lengthwise of the drum to the 45 crushing bodies or material contained therein as the drum rotates. The displacement member or members at the discharge end of the mill may be formed with perforations, and thus serve as a screen or screens for 50 the discharge of the material between the axis and periphery of the drum. The displacement member or members at the feed end of the mill may also be formed with openings of appropriate size, shape and arrangement for introducing the material 55 to be crushed into the drum.

In the accompanying drawing, illustrating some of the preferred embodiments of the invention, like characters designate the same parts in the several figures.

Figure 1 is a substantially vertical longitudinal section on the line 1—1, Fig. 2, of a mill embodying the invention; Fig. 2 is a vertical cross section on the line 2—2, Fig. 1 of the mill; Fig. 3 is an elevation on a reduced scale, of a false head or supporting plate having radial discharge flights, and a central deflector viewed in a plane and direction indicated by the dotted line and arrows 3—3, Fig. 1; Fig. 4 is a sectional detail on the line 4—4, Fig. 2; Fig. 5 is a longitudinal section on the line 5—5, Fig. 6, of a portion of a mill embodying modifications of the invention; and Fig. 6 is a vertical cross section on the line 6—6, Fig. 5.

The mill, as shown in Figs. 1 to 4 inclusive comprises a rotary drum, barrel or shell, which in its general construction may be like or similar to that of ball, pebble or tube crushing or grinding mills in common use.

In the present case the rotary drum or barrel consists of a substantially cylindrical body 1, which may be made as shown, of heavy steel or boiler plate, and heads 2 and 3, which may be made of cast iron and bolted to annular flanges 4, riveted to the ends of the cylindrical body.

The heads 2 and 3 are formed or provided on their outer sides with hollow trunnions 5 and 6, through which the material to be crushed or ground is fed into and discharged from the mill, and which are rotatably mounted in bearings 7; preferably of the spherical or self-adjusting type common in this class of mills.

At one end the mill is provided with a gear 8, which may be of annular form and bolted with the intervening flange ring 4 to the head 2, as shown in Fig. 1, for imparting a rotary movement to the barrel through the medium of a counter shaft parallel with the axis of the barrel and provided with a pinion meshing with the gear, according to wellknown practice, and therefore not shown.

As thus far described the mill may be of substantially the same construction as ordinary well known tube, ball or pebble crushing or grinding mills.

In the operation of such mills, the material to be crushed or ground and the loose crushing bodies, such as balls, pebbles and

the like, tend to lodge in and fill the corners or angles between the body and heads of the barrel and thereby interfere with the free attritive and percussive action of the 5 larger lumps or pieces of material and of the non-friable crushing bodies when they are used, and thus reduce the effective length and capacity of the mills. The material to be crushed also has a tendency to remain in 10 such mills after it has been reduced to the desired size and to become pulverized or further reduced to slimes, or a product of undesirable fineness, which have a cushioning effect and reduce the impact and attritive 15 action of the larger and heavier lumps or pieces of material and of the non-friable crushing bodies when used, thereby materially reducing the capacity or efficiency of the mills, besides resulting in an undesirable 20 product.

To obviate these objections and difficulties in accordance with the present invention, a mill of this type is provided with one or 25 more displacement members which may be variously formed and disposed according to 30 the kind of work to be done and the nature of the material to be treated.

In the mill shown in Figs. 1 to 4 inclusive 35 of the accompanying drawing by way of illustration, a number, in the present case three, displacement members 9, are provided in the feed end of the mill, and a like number of similar displacement members 10, are provided in the discharge end of the mill. 40 These members, which may be of various forms according to the nature of the work to be done and the material to be operated upon, are preferably constructed of steel or hard metal like or similar to that of which 45 40 liners for this class of mills are made, and may be attached or fastened to the barrel in various ways. They are also preferably made as shown, of wedge-shape with deflecting walls or surfaces exposed to the interior 50 of the barrel and extending inwardly from the inner periphery or cylindrical body of the barrel towards its axis at an inclination to planes perpendicular to the axis of the barrel. As shown, these deflecting walls or 55 surfaces are of spirally curved formation, and are of triangular shape, increasing in area and extent into the barrel both axially and radially in a direction opposite the direction of rotation of the barrel indicated by arrows on Figs. 2, 3 and 6 of the drawing.

The displacement members at the feed end 60 of the mill may be disposed in any desired relation to the displacement members at the discharge end. As shown in Fig. 1, the larger ends of the members 9 are arranged approximately opposite the larger ends of the displacement members 10 at the discharge end of the mill, so that the effective 65 length of the crushing chamber within the

barrel is alternately increased and reduced in successive sectors or angular portions of the barrel.

The displacement members either at the feed or discharge end of the mill or at both 70 ends, may be perforated either for the admission of material into the barrel or its discharge therefrom, or for both purposes.

As shown in Figs. 1 and 2, the deflecting walls of the displacement members 10 are 75 formed with apertures 11, to permit the discharge of material through them when it has been crushed or reduced to the desired size. These apertures may be of various shapes and variously disposed over a greater 80 or less extent of the deflecting walls of the displacement members.

The head 3 is preferably of conical or con-cavo-convex form with the concavity on the inner side, and it forms with the displacement members 10, a chamber 12, into which the reduced material is directly discharged through the apertures 11. 85

Between the head 3 and the annular flange 4 to which it is bolted, a supporting plate 13 90 is interposed. This plate, as shown in Fig. 3, is formed with openings 14, corresponding in shape with the deflecting members opposite which they are located, and is formed or provided between the openings with radi- 95 ally disposed flights, wings or scoops 15, for lifting the crushed material discharged into the chamber 12 to and delivering it into the hollow trunnion 6. The central portion of the plate 13 is provided with a deflector 16, 100 divided by wings or partitions into channels registering with the opening between the inner ends of the flights or scoops 15 for directing the material lifted thereby from the chamber 12 into the trunnion 6. 105

Those portions of the body 1, head 2, and supporting plate 13 of the barrel which are exposed between the displacement members 9 and 10 to the interior of the barrel, are protected by steel or hard metal liners, and 110 the liner sections adjoining the displacement members are utilized to fasten them in place in the barrel, the cylindrical body 1 being provided with renewable liner sections 17 and 18, which are bolted or otherwise de- 115 tachably fastened thereto. The sections 18 adjoining the displacement members 9 and 10, are made to conform thereto, and are beveled or otherwise formed at the edges next to the displacement members to over- 120 lap or interlock therewith and hold them in place.

The head 2 at the feed end of the mill is provided with a liner 19, bolted or otherwise 125 detachably fastened thereto and formed with a central opening registering with the opening in the feed trunnion 5. The outer edges of the liner section 19 are beveled to overlap, or otherwise formed to engage with the inner edges of the displacement members 9 130

and to hold them in place. The central portion of the plate 13 is provided with a liner section 20, bolted or otherwise detachably fastened to said plate and beveled or formed at the edges to overlap or interlock with the inner edges of the displacement members 10 and to hold them in place. Liner sections 21, fitting between the displacement members 10 and bolted or otherwise detachably fastened to the radiating portions of the plate 13 between the openings 14 therein, are also beveled to overlap or formed to interlock with the adjoining edges of said displacement members, and assist in securely holding them in place in the barrel. The head 2 is provided with liner sections (not shown) like or similar to the sections 21 in the discharge end of the mill, to fill the spaces between the displacement members 9 and assist in holding them in place.

The barrel is provided, as shown in Fig. 1, with a manhole and removable cover 22, for removing and replacing the displacement members and liner sections. For some kinds of work and some materials, the mill is provided as indicated by dotted lines in Fig. 1, with balls, pebbles or other non-friable crushing bodies 23.

The displacement members 9 at the feed end of the mill may be formed with apertures of appropriate size and arrangement similar to those of the members 10, for the admission into the barrel of the material to be crushed, or for the discharge therefrom of crushed or fine material, and the space or spaces between the head 2 and the perforated deflecting walls of the displacement members 9 may communicate with the hollow trunnion 5 and be utilized in connection therewith for feeding material into the mill or for discharging crushed or fine material therefrom.

The mill, particularly when a barrel of greater length than that shown in Fig. 1 is used, may be provided at one or more points between its ends with displacement members similar to those shown, and the different sections into which the barrel is thus divided may be provided with crushing bodies of different sizes so as to progressively reduce the material, and to effect a classification thereof when desirable.

Referring to Figs. 5 and 6, showing the feed end of a mill having a barrel 1' of greater length than diameter, double displacement members 24 having oppositely inclined deflecting walls or surfaces of increasing area and extent both axially and radially into the barrel in a direction opposite the direction of rotation, like or similar to the displacement members 9 and 10, shown in Figs. 1 and 2, are provided at one or more intermediate locations between the ends of the mill and partially divide it into com-

partments or sections which may be supplied as indicated with crushing bodies 23 of different sizes.

The hollow displacement members 9' are formed with openings 11' for admission of material into the barrel and the adjacent head 2', like the head 3, is of conical shape and forms with said displacement members and an interposed plate 13' bolted with the head to the barrel, a chamber 12' into which the material to be crushed is fed through the trunnion 5 and from which it is admitted into the displacement members through openings 14' in said plate. The plate 13' is provided with flights or wings 15', which direct the material from the chamber 12' into the hollow displacement members 9'.

The plate 13' and liner section 19' are formed with central openings 25, which may be utilized for the admission of material into or its discharge from the barrel.

Material to be crushed may be fed into the mill and the crushed material may be discharged therefrom through the same trunnion at either end or both ends of the mill, as for example, the material may be supplied to the mill through a spout or pipe 26 passing through the trunnion 5 and openings 25, as indicated by dotted lines in Fig. 5, the crushed material being discharged through said trunnion outside of the spout or pipe.

With displacement members constructed and arranged at the feed end and at one or more intermediate locations between the ends of the mill, as shown in Fig. 5, perforated displacement members 10 and the construction and arrangement of associated parts, shown in Fig. 1, may be used.

In the operation of the mill as shown in Figs. 1 to 4 inclusive, the material fed into the barrel through the hollow trunnion 5, is carried up on the ascending side of the barrel with the crushing bodies, and when it passes the angle of repose, tumbles back into the lower part of the barrel, thereby causing the larger and heavier lumps or pieces of material and the crushing bodies when used, to break and reduce the friable material by impact and attrition. As the barrel rotates, the material and the crushing bodies when used, are displaced by the inclined deflecting walls of the displacement members 9 and 10 lengthwise of the barrel, and the material rolling or tumbling and sliding over the inclined surfaces of the displacement members one after another, and falling or being crowded back by the weight of the load or charge in the mill over the larger ends of the displacement members into the recesses between them towards the ends of the barrel, is more rapidly crushed and reduced, the traverse of the material and of the crushing bodies and the attritive and percussive action of the larger and heavier lumps or pieces of material and of

the crushing bodies being materially increased with each revolution or partial revolution of the drum, and the tendency of the material and crushing bodies to lodge and 5 remain in an inert state in the corners or angles between the cylindrical body and the heads of the drum, being prevented.

The displacement members 9 and 10 being arranged as shown, with their larger ends or 10 the portions thereof extending farthest into the barrel opposite one another, operate to compact, condense and raise and to release, loosen and lower the contents of the mill alternately, thereby increasing the crushing, 15 grinding and attritive action of the material upon itself and of the crushing bodies when they are employed.

As the material is reduced to the desired size and is carried in its progress through the 20 mill against the perforated displacement members 10, it is discharged through the apertures 11 into the chamber 12, from which it is lifted by the flights or scoops 15 and delivered thereby into the hollow discharge trunnion 6. As the material slides down over the inclined surfaces of the displacement members 10, it is crowded through the apertures 11 as soon as it is reduced to a size that will pass through said apertures. 25 The discharge of the crushed material is thus facilitated and accelerated, so that it does not remain in the barrel after it has been reduced to the desired size, and hence does not interfere with the crushing action 30 of the larger and heavier lumps or pieces of material and of the crushing bodies when they are used.

The operation of the modified mill shown in Figs. 5 and 6 is essentially like that of 40 the mill shown in Figs. 1 and 2, except as to variations in means and method of feeding or introducing material into the barrel.

Displacement members like or similar to the members 9 at the feed end of the mill, 45 may be employed at the discharge end, and the material as it is crushed and reduced to the desired size, discharged directly through the hollow trunnion 6.

Various changes other than those hereinbefore mentioned, in the construction and arrangement of the displacement members and other parts of the mill may be made without departure from the principle and scope of the invention as defined in the following claims.

I claim:

1. In a crushing mill the combination with a rotary barrel, of a curved wedge-shaped displacement member disposed circumferentially around the interior of the barrel to 60 which it is attached and increasing in extent both radially and axially relative to the barrel in a direction opposite the direction of rotation of the barrel.

65 2. In a crushing mill the combination with

a rotary barrel, of a curved wedge-shaped displacement member disposed circumferentially around the interior of the barrel to which it is attached between its ends and of increasing extent both radially and axially relative to the barrel in a direction opposite the direction of rotation of the barrel which is thus partially divided into compartments.

3. In a crushing mill the combination with a rotary barrel, of a wedge-shaped displacement member fixed to and extending inwardly from the inner periphery of the barrel and having a spirally curved deflecting surface inclined both axially and radially to a plane perpendicular to the axis of the 80 barrel and increasing in area in a circumferential direction opposite the direction of rotation.

4. In a crushing mill the combination with a rotary barrel, of displacement members 85 having deflecting surfaces inclined to planes perpendicular to the axis of the barrel, the deflecting surfaces of the displacement members at opposite ends of the barrel being so disposed relative to one another as to alternately lengthen and shorten the interior of the barrel in successive angular portions thereof.

5. In a crushing mill the combination with a rotary barrel, of wedge-shaped displacement members having deflecting surfaces extending inwardly from the inner periphery of the barrel adjacent to its ends, said members increasing in width and radial and axial extent into the barrel in a circumferential 100 direction opposite the direction of rotation, and the larger ends of the members at opposite ends of the barrel being located approximately opposite each other.

6. In a crushing mill the combination with a rotary barrel, of a displacement member adjacent to one end of the barrel and having a perforated deflecting wall extending inwardly from the inner periphery of the barrel at an inclination to a plane perpendicular 110 to the axis of the barrel, said member increasing in width in a direction opposite the direction of rotation.

7. In a crushing mill the combination with a rotary barrel provided with a head having 115 a hollow trunnion, and a displacement member having a perforated deflecting wall extending inwardly from the inner periphery of the barrel at an inclination to a plane perpendicular to the axis of the barrel adjacent to said head and forming therewith a chamber in communication with the hollow trunnion and through the perforations in the deflecting wall of the displacement member with the interior of the barrel.

8. In a crushing mill the combination with a rotary barrel provided with a head having a hollow discharge trunnion, of displacement members having spirally curved perforated walls extending inwardly from the inner pe- 130

riphery of the barrel adjacent to said head, with which they form a discharge chamber.

9. In a crushing mill the combination with a rotary barrel provided with a head having a hollow feed trunnion, of a curved wedge-shaped displacement member having an opening therein and disposed circumferentially around the interior of the barrel to

which it is attached adjacent the head with which it forms a feed chamber communicating through said opening with the interior of the barrel. ¹⁰

In witness whereof I hereto affix my signature.

FRANCIS O. WILLIAMSON.
